CLAIM

The ornamental design for a modular test plug, as shown and described.

DESCRIPTION

FIG. 1 is a top, front and right side perspective view of a modular test plug showing our new design;

FIG. 2 is a bottom view thereof;

FIG. 3 is a top view thereof;

FIG. 4 is a rear view thereof;

FIG. 5 is a front view thereof;

FIG. 6 is a left side view thereof; and,

FIG. 7 is a right side view thereof;

The broken line portion of the figure drawings is included to show unclaimed subject matter only and forms no part of the claimed design.
